UNITED STATES PATENT OFFICE.

JOHN THOMAS BATTs, OF GRAND RAPIDS, MICHIGAN.

DESIGN FOR A GARMENT-HANGER BRACKET.

60,640.

Specification for Design. Patented Mar. 21, 1922.

Application filed January 3, 1921. Serial No. 434,803. Term of patent 3½ years.

To all whom it may concern:

Be it known that I, JOHN THOMAS BATTs, a citizen of the United States, residing at the city of Grand Rapids, in the county of Kent and State of Michigan, have invented a new, original, and ornamental Design for a Garment-Hanger Bracket, of which the following is a specification, reference being had to the accompanying drawing, forming a part thereof.

In the drawing,
Fig. 1 is a side elevation of the bracket of my design, and
Fig. 2 is a front end view thereof.

I claim:

The ornamental design for a garment hanger bracket, substantially as shown.

In testimony whereof, I hereunto affix my signature.

JOHN THOMAS BATTs.
